UNITED STATES PATENT OFFICE.

GEORGE H. JOHNSON, OF ROCKFORD, ILLINOIS.

DOOR-LOCK.

1,165,102.

Specification of Letters Patent. Patented Dec. 21, 1915.

Application filed September 5, 1914. Serial No. 860,397.

To all whom it may concern:

Be it known that I, GEORGE H. JOHNSON, a citizen of the United States, residing at Rockford, in the county of Winnebago and 5 State of Illinois, have invented certain new and useful Improvements in Door-Locks, of which the following is a specification.

An object of my invention is to provide a door lock of the spring latch type which 10 has the parts thereof so arranged that the turning of the knob spindle to release the latch from its engaged position is precluded except a key of a special form and design be used to release mechanisms which become active to lock the bolt against movement to the released position.

A further object is to so construct the lock that the keyway is through the spindle of the knob and thus the key and knob are 20 so located as to permit the two to be operated simultaneously or coincidentally.

With other objects in view, which will be referred to, my invention consists in the peculiar combination and novel arrangement of parts, such as will be hereinafter 25 more fully described in connection with the accompanying drawings and more particularly pointed out in the appended claims.

In the drawings:—Figure 1 is a view in 30 side elevation of my improved lock. Fig. 2 is a view similar to Fig. 1 with the side plates of the case of the lock removed and with parts illustrated in section. Fig. 3 is a transverse vertical sectional view on the line 3—3 of Fig. 1. Fig. 4 is a detail perspective view of a form of key which may be adapted for use with my invention. Fig. 5 is a fragmentary sectional view taken on the line 5—5 of Fig. 6. Fig. 6 is a horizontal 35 fragmentary sectional view taken on the line 6—6 of Fig. 5.

The case of the lock comprises the body portion 1 and the cover plate 2 which is to be secured to the body portion by the screws 45 3 or other suitable fastening means and a bearing partition 4 is provided within the body member 1 to extend parallel with the ends thereof. A bolt 5 is slidably mounted in orifices formed in alinement through the 50 end wall 6 of the body member and through the partition 4 disposed therein and a coil spring 7 is received around this lock bolt 5 to bear against the partition 4 and against an abutment pin 8 which is passed through 55 the bolt 5 and which with the parts in the locked relation rests against the inner wall

of the end 6 to prevent too great extension of the bolt 5 and to be maintained in a relation to be readily operable.

The knob spindle 9 which is made tubular in form is passed through bearings provided through the side plates of the body member 1 and through the cover plate 2, this spindle 9 being preferably mounted to be in alinement with the longitudinal extent of the bolt 5 and having the pins 10 and 11 carried thereby to prevent endwise displacement from the proper mounting. A yoke 12 is secured across the inner end of the bolt 5 and has the ends thereof formed into eyelet loops. Bracket arms 13 are provided to project from the spindle 9 to lie in a substantially vertical plane when the parts are in their normal position as is illustrated in Fig. 2 and links 14 are connected 75 from each of the eyelet loops of the yoke 12 to the arms 13 in such a manner that the turning of the knob spindle 9 through the grasping and turning of the knob 15 will cause a tension to be exerted upon one of the links 14 to draw the bolt 5 within the casing against the tension of the spring 7 and to release this bolt from its operative engagement.

With the parts in the relation as above 85 described, all that is necessary to draw the bolt from its operative relation is the turning of the knob 15, however, it is desirable that some means to preclude turning the knob and consequently of the spindle 9 90 be provided. To this end, the bolt 5 has the bracket arm 16 carried on the inner end thereof adjacent the mounting of the yoke 12, a stop lever 17 is pivoted near its center at 18 to swing to a relation that one arm 95 thereof rests back of and against the bracket arm 16 to prevent movement of the bolt in a direction to withdraw this bolt from its operative relation, the free and unengaged end of the lever 17 being sufficiently heavy 100 that this lever will be swung to the position as hereinbefore set forth and the pins 19 being provided to prevent too great movement of the lever in either direction.

The spindle 9 is slotted transversely at 105 20 as is better illustrated in Figs. 5 and 6 and the upper arm of the lever 17 is bent to a shape to rest within the cut-away portion. A key-check 21 preferably made of spring sheet metal is secured to the case body 1 to 110 extend into the slot 20 of the spindle 9 and this key-check member 21 is bifurcated at

its upper end adjacent the disposition of the arms of the lever 17 which is embraced by the slot 20.

A key 22 has the shank thereof made 5 tubular and of a diameter to fit within the bore of the spindle 9 and at its inner end this key is shaped as at 23 to engage against the key check member 21 so that the arm provided by the bifurcation will rest within 10 the notches 24 of the key and as the key is inserted in the bore of the spindle 9 and is turned this engagement with the check member 21 and with the arm of the lever 17 will be sufficient to move the parts to the 15 relation indicated in dotted lines in Fig. 5 where the arm of the lever 17 engaged with the bracket arm 16 will be swung to a position to permit back movement of this bracket arm and will consequently allow 20 turning of the knob 15 and through the interconnection of the parts the withdrawal 25 of the bolt 5 from its operative or locked position. It will be understood that the spindle 9 must be kept free and have the passage thereof unobstructed to a point adjacent the notch or slot 20 and it may be found desirable to pass the pin 10 entirely through this knob to form an abutment bearing for the key and to insure that the 30 key when inserted in the bore of the spindle will be brought to the proper operating relation.

From the foregoing it will be seen that I have provided a door lock which has the 35 parts thereof so constructed and arranged that the normal tendency of the mechanism is to hold the bolt in a locked relation and turning of the knob to withdraw the bolt from this relation is prevented under ordinary circumstances and is permitted only by the insertion of a key and turning of this key in conjunction with the knob.

While I have herein shown and described one specific form of my invention, it will be understood that slight changes might be made in the form and arrangement of the several parts without departing from the spirit and scope of my invention, and hence I do not wish to be limited thereto except 50 for such limitations as the claims may import.

I claim:—

1. A door lock comprising a locking bolt, a spring connected with said locking bolt to normally hold the bolt in a locked relation, a bracket arm carried by said bolt, a lever pivotally mounted adjacent its center to have one of the arms thereof swing to a position behind said bracket arm to prevent 60 withdrawal of the bolt against the tension of the spring and said lever arranged to automatically swing to an operative relation upon movement of the bolt to the locked position, a hollow spindle provided with a 65 slot therein mounted at a point to have the

free arm of the lever received within the slot, and a key to be received through the hollow spindle to displace said free arm to move the lever from engagement behind the bracket arm and to thus permit withdrawal of the bolt from the locked position. 70

2. A door lock comprising a locking bolt, a spring connected with said locking bolt to normally hold the bolt in a locked relation, a bracket arm carried by said bolt, a 75 lever pivotally mounted adjacent its center to have one of the arms thereof swing to a position behind said bracket arm to prevent withdrawal of the bolt against the tension of the spring, a hollow spindle provided with a slot therein and mounted at a point to have the free arm of the lever received therein, a key to be received through the hollow spindle to displace said free arm to move the lever from engagement behind the 80 bracket arm and to thus permit withdrawal of the bolt from the locked position, and a key-check projecting into the slot of said hollow spindle to permit turning thereof and to preclude the entrance of an unauthorized key. 85

3. A door lock comprising a locking bolt, a spring connected with said locking bolt to normally hold the bolt in a locked relation, a bracket arm carried by said bolt, a 90 lever pivotally mounted adjacent its center to have one of the arms thereof swing to a position behind said bracket arm to prevent withdrawal of the bolt against the tension of the spring and said lever arranged to automatically swing to an operative relation upon movement of the bolt to the locked position, a hollow spindle provided with a slot therethrough arranged at a position to have the free arm of said lever located within the slot, a yoke carried by said hollow spindle, a connection from each end of said yoke to the bolt, and a key to be inserted within the hollow spindle and engaged with the free end of the lever to disengage the 100 same from the bracket arm and thus permit withdrawal of the bolt upon turning of the spindle in the one direction or the other. 105

4. A door lock comprising a case, a bolt mounted in the case to be capable of end-wise sliding movement, a spring to resiliently hold said bolt in a thrown position, a hollow spindle mounted through the case and provided with a slot therein, a yoke carried by said hollow spindle, a second 110 yoke carried by the inner end of said bolt, link connections between said yokes arranged in a manner that upon turning of the spindle in the one direction or the other the bolt is withdrawn against the tension of the spring, a bracket arm carried by the inner end of said bolt adjacent the disposition of the yoke thereon, a lever pivotally mounted adjacent its center to have one of the arms thereof received behind said bracket 115 120 125 130

arm and the remaining arm received within the slot of the hollow spindle, a key to be inserted through said hollow spindle to engage with the arm of the lever received 5 within the slot to turn the same about its pivotal mounting and to engage the lever from the bracket arm, and stop means carried by the key to project within the bore of the hollow spindle through said slot and 10 thus prevent the use of an unauthorized key.

5. A door lock comprising a body, a locking bolt mounted therein to be capable of endwise sliding movement, a spring to normally hold said bolt extended from the case 15 in a locked relation, a hollow spindle mounted in the case and provided with a slot therethrough, means connected between said bolt and spindle in such relation that upon turning of the spindle the bolt is withdrawn 20 against the tension of the spring, a bracket arm carried by the bolt, a lever pivoted to have one arm thereof swing to a position behind said bracket arm and to hold the bolt against withdrawal and said lever arranged 25 to automatically swing to an operative relation upon movement of the bolt to the locked position, a key to be inserted through the hollow spindle to engage with said lever and swing the lever from the position of 30 abutment against the bracket arm, and said parts so arranged that as the lever is swung

from the position of abutment the knob may be turned to withdraw the bolt against the tension of the spring.

6. A door lock comprising a case, a bolt 35 slidably mounted in said case, a coil spring received around said bolt to hold the bolt normally extended from the case and in a locked position, a hollow spindle mounted through the case having a slot formed therethrough in that portion embraced within the case, means connected between said spindle and bolt in such relation that turning of the spindle causes the bolt to be withdrawn from its extended position against the tension of the spring, a bracket arm carried by said bolt, a lever pivoted to the case to swing to a position to engage behind said bracket arm and prevent withdrawal of the bolt and having a portion thereof extended to a point 50 within the slot of the spindle, a key to be inserted through the hollow spindle to engage with said lever to swing the lever from its position of abutment against the bracket arm, and a key check to prevent the use of 55 an unauthorized key.

In testimony whereof I affix my signature in presence of two witnesses.

G. H. JOHNSON.
